(57) **CLAIM**

The ornamental design for an erectile device, as shown and described.

DESCRIPTION

FIG. 1 is a rear view of an erectile device in accordance with the present invention;

FIG. 2 is a front view of an erectile device in accordance with the present invention;

FIG. 3 is a right side view of an erectile device in accordance with the present invention;

FIG. 4 is a left side view of an erectile device in accordance with the present invention;

FIG. 5 is a bottom view of an erectile device in accordance with the present invention;

FIG. 6 is a top view of an erectile device in accordance with the present invention;

FIG. 7 is a perspective view of an erectile device being worn by a person in accordance with the present invention;

FIG. 8 is a rear view of an erectile device in an unhooked configuration in accordance with the present invention;

FIG. 9 is a right side view of an erectile device in an unhooked configuration in accordance with the present invention;

FIG. 10 is a front view of an erectile device in an unhooked configuration in accordance with the present invention;

FIG. 11 is a left side view of an erectile device in an unhooked configuration in accordance with the present invention;

FIG. 12 is a top view of an erectile device in an unhooked configuration in accordance with the present invention; and, FIG. 13 is a bottom view of an erectile device in an unhooked configuration in accordance with the present invention.

Portions of FIG. 7 shown in broken lines are for the purpose of illustrating the environment in which the article embodying the design is used and form no part of the claimed design.
